United States Patent Office.

WALES A. CANDEE AND WILLIAM C. RICHARDS, OF BRISTOL, CONNECTICUT.

Design No. 3,710, dated October 12, 1869.

DESIGN FOR A BOTTLE.

The Schedule referred to in these Letters Patent and making part of the same.

We, WALES A. CANDEE and WILLIAM C. RICHARDS, both of Bristol, in the county of Hartford, and State of Connecticut, have invented and produced a new and original Design for a Bottle, of which the following is a specification, reference being had to the accompanying drawings, in which—

Figure 1 is a side elevation of our design, and

Figure 2, a transverse section through the centre of its length.

A designates the sides of the body of the bottle, which is the widest in the middle, and tapering toward each end.

a designates the sunken panel, or portion of the sides in imitation of panels.

The body or main portion of the bottle has only three sides, a transverse section of which forms an equilateral triangle.

The upper end of the bottle we provide with a neck, B, and the lower end with a base, C.

Claim.

We claim, as our invention, the design for a bottle, herein shown and described.

WALES A. CANDEE.
WM. C. RICHARDS.
